(57) **CLAIM**

The ornamental design for a sports crossover vehicle body, as shown and described.

DESCRIPTION

FIG. 1 is a front perspective view of a sports crossover vehicle body, showing my new design;

FIG. 2 is a rear perspective view thereof, showing the turn signals, in pairs around the vehicle;

FIG. 3 is a side view thereof, showing the twin exhausts beneath the rear passenger door;

FIG. 4 is a rear view thereof;

FIG. 5 is a front view thereof;

FIG. 6 is a rear perspective view thereof, showing the rear windshield open; and,

FIG. 7 is a rear perspective view thereof, showing the rear gate open.

The wheels shown in broken lines are for illustrative purposes only and form no part of the claimed design.
